UNITED STATES PATENT OFFICE.

JOSEPH DAVIS LACROIX, OF BALTIMORE, MARYLAND, ASSIGNOR TO THE WILSON DISTILLING COMPANY, OF JERSEY CITY, NEW JERSEY, A CORPORATION OF NEW JERSEY.

SPINNING-MACHINE FOR BOTTLES.

1,199,908.

Specification of Letters Patent.

Patented Oct. 3, 1916.

Application filed November 25, 1912. Serial No. 733,408.

To all whom it may concern:

Be it known that I, JOSEPH D. LACROIX, a citizen of the United States, residing at Baltimore, county of Baltimore, and State 5 of Maryland, have invented certain new and useful Improvements in Spinning-Machines for Bottles, fully described and represented in the following specification and the accompanying drawings, forming a part of 10 the same.

This invention relates to capping machines, and in particular to machines adapted to seal caps upon receptacles by spinning.

One object of the invention is to produce 15 a machine having an improved manually operable feeding and controlling device.

Another object is to produce a machine of simple construction, capable of working efficiently and at a high rate of speed.

20 Still another object is to produce a machine which may be adapted for the sealing of caps upon bottles where the cap and the bottle combined form a non-refillable receptacle.

25 Still other objects of invention are included in the following description and claims.

Referring to the drawings: Figure 1 is a side elevation of the complete machine; Fig. 30 2 is a front elevation of the same; Fig. 3 is a sectional elevation of the spinner mechanism; Fig. 4 is a sectional plan along the line 4—4 of Figs. 1 and 3; Fig. 5 is a sectional plan of the spinning mechanism 35 through line 5—5 of Fig. 3; Fig. 6 is a sectional plan taken on the line 6—6 of Fig. 3; Fig. 7 is a section taken on the line 7—7 of Fig. 3; Fig. 8 is a sectional elevation taken on line 8—8 of Fig. 4; Figs. 9 and 10 40 are sectional elevations of the holder and elevating mechanism; and Fig. 11 is a sectional elevation of the spinning mechanism.

The particular mechanism herein shown as disclosing the invention comprises a machine for the sealing of caps to bottles where the combined cap and bottle form a non-refillable receptacle. The machine consists broadly in a bottle holder which may be elevated by a foot lever or pedal, a power

driven spinning device in alinement with 50 the holder, and a lever to control both the engagement of the spinning device and bottle cap, and the spinning operation.

The main frame of the machine comprises the base 10 and a vertical tubular standard 55 11. As shown in Figs. 1, 2, and 10, the bottle holder 12, equipped with a centering device 13, is carried on the end of a vertical plunger which slides in brackets 14 and 15 bolted to standard 11. The plunger comprises a tubular shaft 16 threaded to a solid shaft 17 as shown, and is provided with a lock nut 18 to secure the parts firmly together, this construction permitting the bottle holder 12 to be adjusted to any desired 60 height. The solid shaft 17 is splined to the lower bracket 15 as indicated at 19 so that the holder cannot rotate.

The bottle holder is moved upward by a 65 pedal mechanism best shown in Figs. 1, 9 70 and 10. To shaft 17 of the plunger a cross-head 20 is fastened by set screws 21, 21. A pair of links 22, 22^a connect the cross-head with a cam-arm 23 which is pivoted to the bracket 15 at 24. The pedal 25 is fulcrumed 75 to the base 10 at 26 and at its inner end carries a roller 27 which engages the cam-arm 23. The fulcrum block 26 normally floats upon springs 28, 28 (Figs. 1 and 2) and has a slight vertical cushioning movement with 80 in the lugs 29, 29 of the base 10. A pair of coacting serrated stops 30, 30^a are attached to pedal 25 and base 10 respectively, and when the pedal is depressed, as shown in Fig. 2, these stops engage each other and 85 the fulcrum 26 then becomes locked in a fixed position. The stops are serrated so that they may engage each other and lock the fulcrum regardless of the extent to which the fulcrum may be vertically displaced. The pedal is kept normally elevated by a compression spring 31, spring 90 plunger 32 and sleeve 33. The plunger 32 is pivoted to the pedal at 34 and the sleeve 33 is swiveled to the frame at 35.

95 In operation, after the bottle is placed in the holder 12, the pedal is depressed against the pressure of spring 31, the roller 27 cam-

ming the arm 23 upward which in turn causes the holder plunger to move upward in brackets 14, 15 bringing the bottle and cap into position to be operated upon by 5 the spinning devices.

The floating fulcrum 26 will absorb any undue shock that may be caused by a too rapid depression of the pedal, while the stops 30, 30^a will lock the fulcrum in position 10 after the upward movement of the holder has taken place, so that when the bottle is finally positioned to be operated upon, the holder will form a rigid abutment to resist the pressure of the spinning 15 device.

The spinning device is adapted to seal hermetically together the cap and bottle by spinning a sleeve upon them. The method is disclosed in Fig. 11 in which the 20 bottle is shown at 36 and the cap at 37. The cap has a groove 37^a while the bottle has two similar grooves 36^a, 36^b. The sleeve or ferrule 38, as shown in Fig. 3, is provided with a flange 39 by which it may be set into 25 position upon the cap and may also serve to hold the cap in alinement with the bottle. The sleeve is spun into the grooves 37^a, 36^a, 36^b, firmly binding the cap and bottle together, as shown in Fig. 11, and during 30 the spinning the sleeve 38 is drawn or ironed out, as indicated in Figs. 3 and 11. This method of spinning, together with the spinning mechanism to be first described, form the subject-matter of a co-pending application filed October 24, 1912, Serial No. 35 727,492, and is disclosed here only so far as is necessary to illustrate the present invention. This spinning mechanism comprises three coöperating devices: plungers 40 operating together to center the cap, to hold it in position upon the bottle, and to clamp the sleeve in position for spinning; mechanism to move the spinning rolls along the sleeve; and mechanism to vary the pressure 45 of the spinning rolls upon the sleeve.

The centering and holding plungers are shown in Figs. 3 and 11. Centrally located in the spinning mechanism is a tube 40, the upper end of which is anchored to a bracket 50 41 by threaded engagement and a lock nut 42; the bracket 41 being bolted to the frame 11. The intermediate part of the tube 40 contains a spring 43 and a shouldered plunger 44 the lower end of which terminates in 55 a centering head 45. The lower part of tube 40 is enlarged to form a cylinder within which a second and stronger spring 46 is located and also a second plunger 47, the plunger 44 passing freely through the 60 spring 46 and the second plunger 47. At the lowest point on the tube 40, at the bottom of the cylindrical enlargement, is a tubular jaw 48. These devices operate as follows: When the bottle and cap are elevated

as previously described, the cap 37 of the 65 bottle first comes into contact with the centering plunger head 45, which acts to center the cap and bottle as the holder continues its upward movement, the movement at the same time driving back the plunger 70 head 45 and compressing the spring 43. Just before the holder reaches its upward limit of motion, the head 45 comes into contact with the lower end of the second plunger 75 47, whereupon additional pressure is put upon the cap by the compression of spring 46. This position of parts is shown in Fig. 11. At the last instant of the upward movement of the holder, as also shown in the same figure, the tubular jaw 48 comes into 80 contact with the flange 39 of the sleeve or ferrule 38 and clamps that part of the sleeve firmly to the cap.

The spinning rolls are shown at 49, 49 in Figs. 6 and 11, and are carried by arms 50, 85 50 pivoted with their respective shafts 51, 51 at equal distances from one another upon a spinner head 52. The head 52 is carried at the lower end of a rotary sleeve 53 which surrounds the plunger mechanism described 90 above and is concentric with the fixed tube 40. As shown in Fig. 3, the upper end of the sleeve is splined at 54 and is slidable through a sleeve 55 which is attached to the bracket 41 and supports a pulley 56. The pulley rotates the sleeve 53 through a feather 57 engaging the spline 54, the sleeve 55 acting 95 as a bearing therefor.

By the construction thus described, the splined sleeve 53 and spinner head 52 may 100 be given a continuous rotary motion, while at the same time they are longitudinally movable.

The pressure of the spinning rolls upon the sleeve to be spun is varied by the mechanism shown in Figs. 5 and 11. As shown in Fig. 5, the shafts 51, 51 carrying the spinning rolls 49, 49 are equipped with arms 58, 58 to which are fastened resilient members 59, 59 terminating at their inner ends in anti-friction balls 60, 60. These balls normally contact with a hollow cone 61 which is slidable longitudinally upon the spinner head 52 and spinner sleeve 53. The cone 61 has a groove 62 through which it is engaged by 115 63, the yoke being attached to a rack 64 which is slidable in a bracket 65 bolted to the frame and forming a support for the spinning mechanism.

The spinning mechanism is equipped with 120 an automatic counter to register the number of bottles capped by the machine. As shown in Fig. 3, a rod 66 is located within the upper part of tube 40 and projects above the tube where it may make contact with the 125 pawl arm 67 of a register 68 mounted upon the frame (Figs. 1 and 2). This rod is weighted at 69 and is raised to operate the

register by plunger 44 whenever the latter is raised in a capping operation, as previously described.

The spinning mechanism so far described 5 forms no part of the present invention in itself and is further disclosed in the co-pending application mentioned above.

It will be noticed that the mechanism must further be provided to rotate the spinning head; to reciprocate it in a vertical direction; and to control the radial movement and pressure of the spinning rolls.

For the purpose of rotating the spinning head, a suitable prime mover, as an electric 15 motor 70 mounted upon a bracket 71 attached to the frame 11 may be used. This motor by means of a belt 72, idle pulleys 73, 73, may drive the spinning head through pulley 56 above described.

20 The spinning head is reciprocated vertically by a rack 74 (Figs. 3 and 4) which is fastened to a sleeve 75 surrounding the spinning head sleeve 53 and having a sliding bearing in the bracket 65. The sleeve 75 is 25 confined within shoulders on sleeve 53, so that any longitudinal movement of the sleeve 75 will carry with it the sleeve 53, at the same time allowing the latter to rotate freely. As shown in Figs. 1 and 3, the spinning head 52, 30 sleeve 53, sleeve 75 and rack 74 are held normally in their highest position by a counter-weight 76, connected with them by a chain 77 running on pulleys 78, 78.

As best shown in Fig. 4, bracket 65 carries 35 a shaft 79 that may be rotated or moved longitudinally. Upon this shaft a sleeve 80 is loosely positioned, carrying a spur gear 81 meshing with rack 74. To the outer end of sleeve 80 is keyed an arm 82 to which is ful- 40 crumed at 83 a lever 84 which is pivoted to shaft 79 at 85. When the lever 84 is depressed, the lever and arm 82 rotate with shaft 79 about the axis of the latter, at the same time rotating the sleeve 80 and gear 81, 45 causing the spinning head to descend.

The radial movement and pressure of the spinning rolls is controlled through rack 64 described above. This rack meshes with a gear 86 forming part of a second sleeve 87 50 mounted loose upon shaft 79. The sleeve 87 is equipped with opposite diagonal slots 88 which are engaged by a key 89 forming a part of shaft 79. When the lever 84 is moved from right to left about fulcrum 83 55 as a center, as viewed in Fig. 4, the longitudinal movement of shaft 79 which results causes a rotary movement of sleeve 87 and gear 86, whereupon the rack 64 is downwardly moved and the cone 61 moves the 60 spinning rolls as described.

It will be noticed that the right and left movements of the lever 84, and its up and down movements are independent of each other, so that the position of the spinning

rolls and the pressure of the rolls may be independently determined, or may be coördinated in a single movement of lever 84. This permits the sleeves to be subjected simultaneously to a spinning process and to a drawing or ironing out process as well. In 70 this way the joining sleeve may be held under an increasing drawing tension during the spinning operation, resulting in an unusually tight and permanent joint.

The invention is disclosed in connection 75 with a mechanism specially adapted for the sealing of caps to non-refillable bottles; but it is to be understood that the invention is not restricted to this particular illustrative mechanism as it also includes all machines 80 in which caps and receptacles of any description are sealed together. It is obvious also that many changes may be made in the details of the mechanism disclosed without departing from the spirit of the invention, 85 so that the invention is not to be limited to the particular structure and specific details herein disclosed.

What is claimed is:

1. In combination, a spinning tool, means 90 to revolve the tool about an axis, mechanism to move the tool longitudinally in relation to the axis, devices adapted to force the tool toward the axis with a variable pressure, a lever, the said mechanism and said devices 95 being adapted to act upon the tool independently of one another, but each being selectively controlled by said lever.

2. In combination, a resilient spinning tool, means to revolve the tool about an axis, 100 mechanism to move the tool longitudinally in relation to the axis, devices adapted to force the tool toward the axis, and a manually operable lever controlling jointly or selectively the said mechanism and the said 105 devices.

3. In combination, a spinning tool, means to revolve the tool about an axis, mechanism to move the tool longitudinally in relation to the axis, devices adapted to force the tool 110 toward the axis with a variable and resilient pressure, and a manually operable lever controlling jointly or selectively the said mechanism and the said devices.

4. In combination, a holder, a foot lever, 115 connections between the holder and foot lever whereby the holder may be elevated by said lever, a cushioned fulcrum for the lever, and means to lock the fulcrum in a rigid position.

5. In combination, a holder, a foot lever, connections between the holder and foot lever whereby the holder may be elevated by said lever, a cushioned fulcrum for the lever, and means operating automatically to lock the 125 fulcrum in a fixed position when said holder is in an elevated condition.

6. In a bottle capping machine, the shaft

79, sleeve 80 mounted thereon, arm 82 keyed to sleeve 80, lever 84 pivoting on arm 82 and shaft 79, the slotted sleeve 87 loosely mounted on shaft 79 and prevented from 5 endwise movement, key 89 carried by the shaft and engaging the slotted sleeve, gear 81 attached to sleeve 80 and gear 86 attached to sleeve 87 substantially as described.

Copies of this patent may be obtained for five cents each, by addressing the "Commissioner of Patents, Washington, D. C."

In testimony whereof, I have hereunto set my hand, in the presence of two subscribing 10 witnesses.

JOSEPH DAVIS LACROIX.

Witnesses:

JULIA B. ROBINSON,
M. C. MASSIE.

It is hereby certified that in Letters Patent No. 1,199,908, granted October 3, 1916, for an improvement in "Spinning-Machines for Bottles," an error appears requiring correction as follows: In the grant, in the heading and signature to the printed specification the name of the patentee was erroneously written and printed as "Joseph Davis Lacroix," whereas said name should have been written and printed as *Joseph Davis Lacroix*; and that the said Letters Patent should be read with this correction therein that the same may conform to the record of the case in the Patent Office.

Signed and sealed this 19th day of December, A. D., 1916.

[SEAL.]

R. F. WHITEHEAD,

Acting Commissioner of Patents.
